PENCIL

Jesse J. Robbins, Hollywood, Calif., assignor to
Stylofede Corporation, a corporation of California

Application October 29, 1932, Serial No. 640,315
Renewed February 25, 1936

17 Claims. (Cl. 120—17)

My invention relates to pencils, and more particularly to pencils provided with means for renewing the lead when it becomes worn or broken.

Heretofore difficulties have been experienced in putting new lead into the feeding mechanism for a pencil of this type. Generally it was necessary to unscrew the top of the pencil, remove a lead from a compartment and to manually insert this new lead in the feeding means for the pencil. This operation was tedious, often involving the breaking of the lead and dirtying of the hands, and most important of all, loss of time. In cases where shorthand work is performed, as in reporting, or in cases where numbers are taken by telephone operators, the breaking of pencils involves a distinct loss of time. Moreover, even with a number of pencils at the start of the work, all of the points may be broken or worn out before the work is completed, thus necessitating a recess for resharpening pencils. Where refill pencils are used, when the lead in a single filling has been used up, the operation of the refill, as above set forth, requires considerable time.

Moreover, in constructions of the prior art, the refill types of pencil were delicate in mechanism and subject to damage in use.

It is an object of my invention to permit a lead, when it is worn out or broken, to be readily replaced with a minimum of effort, and in a fraction of the time such an operation has heretofore involved.

A further object of my invention is to devise a pencil which is sturdy and simple in operation, and not easily damaged by use.

A still further object of my invention is to provide a pencil which can be manufactured at a small cost from few parts, and which can be readily repaired and replaced.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawing means for carrying the same into practical effect without limiting the improvements in their useful applications to the particular constructions, which, for the purpose of explanation, have been made the subject of illustration.

In the drawing:

Figure 1 is a cross section taken through the longitudinal axis of my pencil;

Fig. 2 is a cross section taken on the line 2—2 of Fig. 1, looking in the direction of the arrows;

Fig. 3 is a detail partly in cross section of the clutch mechanism of the pencil, showing the point supporting tube in its uppermost position;

Fig. 4 is a detail showing the clip on the cap of the pencil;

Fig. 5 is a cross sectional view taken on the line 5—5 of Fig. 1;

Fig. 6 is a cross sectional view taken on the line 6—6 of Fig. 1;

Fig. 7 is a cross sectional view taken on the line 7—7 of Fig. 1.

In the drawing I have shown a pencil body 1, of some suitable material, such as hardened rubber. In the pencil body 1 is inserted a tapered head 2, which may be of metal, hardened rubber, or other suitable material, provided with a shoulder 3 which abuts against the body 1, and has a projecting cylindrical portion 4.

The tapered head 2 is provided with a cylindrical aperture 5, and a larger cylindrical aperture 6. Adapted to reciprocate within the tapered head 2 is a point supporting tube 7 having a conical end 8, through which is adapted to project a writing lead 9.

The point supporting tube 7 is provided with an enlarged cylindrical portion 11 which fits within the counter-bored aperture 6 of the head 2. The point supporting tube is adapted to reciprocate to the position shown in Figure 3 upon pressure being applied thereto, and this reciprocation of the point supporting tube 7 operates to move the lead 9 into the writing position shown in Figures 1 and 2, as will be described. Screw-threaded at 12 into the point supporting tube 7 is a driving tube 13 of lesser diameter than the enlarged cylindrical portion 11 of the point supporting tube. Surrounding the driving tube 13 is a helical spring 14 whose lower end bears against the enlarged cylindrical portion 11 of the point supporting tube 7. The other end of the spring 14 abuts against a partition member 15 provided at 16 with an annular shouldered recess.

Fitting within the shouldered recess 16 is a cylindrical shell 17 which lies with a reasonably tight fit against the interior surface of the hollow pencil body 1. A fixed rack supporting member 18 has one end abutting against the partition member 15, and is held in place by a holding screw 19. The fixed rack supporting member 18 is pro-

vided with two racks, one at each side, which I have designated by numerals 21.

There is a similar rack supporting member 22 which is movable, and which is adapted to slide 5 within the cylindrical shell 17. This movable rack supporting member 22 is provided with racks 23 and formed with upwardly extending ears 24 at the top end. Pivoted on upwardly extending ears 24, at 25, are two link members 26 carrying a 10 connecting pin 27 at their ends opposite their point of pivoting 25 to the ears 24 of the slideable rack 22. The connecting pin 27 is adapted to slide within obliquely inclined slots 28 made in up-standing sides 29 provided in an integrally formed 15 hopper member and lead tube construction which will now be described.

The hopper and lead tube construction comprises a lead tube 31 provided with cut-out portions 32 at one extremity. The lead tube 31 is 20 adapted to reciprocate within the driving tube 13. The oblique slots 28 of the upstanding sides 29 of the lead tube 31 are so positioned that upon movement of the links 26, causing the connecting pin 27 to move in the slots 28, the connecting pin 27 25 will be moved to carry with it a clutch piece 33 which in its lowermost position will seize against the lead 9 and hold it firmly against the bottom of the lead tube 31, causing the lead 9 to move with the movement of the lead tube 31.

30 Integrally formed with the lead tube 31 is a hopper member 34 of trough shape, having one side of the trough 35 higher than the other, and lying close to the interior wall of the cylindrical shell 17. The other side of the hopper member 34 35 comprises a well 36 of lesser height than side 35. A reservoir is formed in the cylindrical shell 17 for leads 9, by reason of a slideable closure member 37 provided with bracing legs 38 to retain it in its proper position within the cylindrical shell 17, but 40 permit it to slide within the cylindrical shell 17. The closure member 37 is provided with a central aperture 39, see Figure 7, through which the lead 9 may pass, and is suitably fastened at 41 to the hopper 34, and moves therewith.

45 The driving tube 13 is provided with a head 42 having flattened sides 43, and stub shafts 44 projecting from these flattened sides, see Figure 5. Mounted on the stub shafts are pinions 45 which mesh with the racks 21 of the fixed rack supporting member 18, and the racks 23 of the movable rack supporting member 22.

Let us assume that it is desirable to feed more lead through the point supporting tube. The pencil is rotated, so that the side of the trough 36 picks up a lead 9 so that it can slide along the bottom of the trough 34, and the pencil is inclined so that the lead 9 will slide through the aperture 39 in the closure member 37. The lead will pass down along the lead tube 31 until it contacts with 60 the end of the lead next before it. Pressure is brought to bear on the point of the pencil, which pushes in the point supporting tube 7 against the pressure of the spring 14. The point supporting tube 7 carries with it the driving tube 13, which 65 causes the pinions 45 to be moved upwardly into the body of the pencil. Since the pinions 45 mesh with fixed racks 21, the pinions will be rotated, and the movable rack member 22 will be moved through a distance twice as great as the movement of the point supporting member.

70 By reason of the engagement of the pin 27 with the top of the oblique slots 28 in the upstanding sides 29 formed on the lead tube 31, the lead tube 31 will be moved approximately twice the distance 75 that the point supporting tube is moved by the

pressure applied by the user. Tube 31 carries with it the hopper 34 and the slideable closure member 37. The movement of the lead supporting tube 31 is not quite twice the magnitude of the movement of the point supporting tube 7, by 5. reason of the fact there is a certain amount of play permitted in the engagement of the pin 27 with the top of the slots 28.

The position of the parts in which the spring 14 is compressed is shown clearly in Figure 3. 10 Now, let us assume that the pressure is released on the point supporting tube. The spring 14 pushes the point supporting tube downward, which carries with it the driving tube 13 and the pinions 45 in engagement with the fixed racks 21, which 15 causes reciprocation of the movable rack supporting member through racks 23, tending to cause the parts to assume the position shown in Figures 1 and 2. This force of the spring causes the clutch member 33 to clamp tightly against 20 the lead 9 in the lead tube, and to move the lead tube and the lead with it downward approximately twice the distance that the point supporting tube moved in its upward movement, thus 25 feeding the lead 9 through the end of the point supporting tube. This operation, of course, can be repeated to feed more and more lengths of lead through the point supporting tube.

The inner wall of the point supporting tube is conically tapered where the end of the lead tube 30 comes, as at 65. When the lead tube 31 is in its uppermost position, the conical contracted portion 65 exerts no pressure on the end of the lead tube, and the end of the lead tube does not grip the lead 9. This permits the lead 9, and the successive leads in the chain of leads such as shown in Figure 1, to remain, for instance, in the position shown in Figure 3, and it will not be raised by the upward movement of the lead supporting tube 31. The leads 9 are free to slide in the lead supporting tube when the lead supporting tube is raised to the position shown in Figure 3. When the spring, through the chain of operation, as before described, pushes the sliding rack 22 back in the position indicated in Figures 1 and 2, the lead 45 is advanced through the point supporting tube 1.

In the position shown in Figures 1 and 2, the end of the lead tube 31 is slightly compressed by reason of the conical restricted section 65 of the point supporting tube 7, and grips the lead to prevent it 50 being shoved back into the body of the pencil under ordinary writing pressure. The cutout portions 32 of the lead supporting tube 31 permits this compression at this end of the lead supporting tube. By rotating the pencil, new lead is caught in 55 the trough 34, and lead can be continuously fed through the point supporting tube as long as there are new pieces of lead in the reservoir.

There is shown at the end of the lead reservoir a 60 rubber 47, held by a split holder member 48 with a knurled head 49, permitting it to be removed and a new rubber inserted. The splits in the holder member 48 permits it to be compressed to permit renewal of the rubber 47. This rubber and holder member constitute the top of the lead 65 reservoir.

There is a cap member 51, having a cylindrical interior member 52. The cylindrical interior member 52 fits over the cylindrical shell 17. The cap 52 is provided with a longitudinal aperture 70 53 in which rests one end of a spring clip 54, carrying a member 55 which may support the user's name, if desired. The user's name may be stamped on the member 55, or the member 55 may be made of transparent material and the user's name writ- 75

ten on paper and inserted between the transparent material and the spring clip 54.

The spring clip 54 is bent, as indicated at 56, and passes through an aperture 57 made in the cylindrical member 52. The spring clip is again bent in the interior of the cap 51, as indicated at 58, and carries thereon a push button 59, held thereon by clips 61 which fit around the portion 58 of the spring clip. The push button 59 passes through an aperture 62 made through cap 51 and the cylindrical interior member 52. The clip is again caused to change direction, as indicated at 63, and is finally fastened by some suitable means, such as rivets 64, to the interior of the member 52.

By pressing on the push button 59, the spring clip is caused to be pushed upwardly at its free end, which carries the member 55, and this end may fit over the pocket of the user. By pressing on the button 59, the spring clip can be released from the pocket of the user. The cap 51 is, of course, removable for the use of the eraser, there being a sliding fit between the cap and the body proper of the pencil, in other words, between the member 52 and the cylindrical shell 17, which latter projects beyond the body 1 of the pencil.

While I have shown and described the preferred embodiment of my invention, I wish it to be understood that I do not confine myself to the precise details of construction herein set forth, by way of illustration, as it is apparent that many changes and variations may be made therein by those skilled in the art without departing from the spirit of the invention, or exceeding the scope of the appended claims.

35 I claim:

1. In a pencil, the combination of a reservoir for leads, a hopper located in the reservoir to receive a lead by rotation of the pencil, a lead tube to which the hopper feeds, said lead tube integrally formed with the hopper and aligned therewith, a clutch for holding the lead with respect to said tube, and means to reciprocate the lead tube to project the lead.

2. In a pencil, the combination of a reservoir for leads, a hopper located in the reservoir to receive a lead by rotation of the pencil, a reciprocable lead tube in communication with the hopper, clutch mechanism cooperating with the lead tube for holding the lead, a rack to operate the clutch, and means to move the rack to reciprocate the lead tube and feed the lead received.

3. In a pencil, the combination of a reservoir for leads, a hopper located in the reservoir to receive a lead, a reciprocable lead tube integrally formed therewith, and means to grip a lead in one direction of reciprocation of the hopper and lead tube, but to release it in the other direction to feed the lead received.

4. In a pencil, the combination of a reservoir for leads, a hopper located in the reservoir to receive a lead, a reciprocable lead tube integrally formed therewith, a clutch for holding the lead in the tube, and means to reciprocate the lead tube to project the lead.

65 5. In a pencil, the combination of a reservoir for leads, a hopper located in the reservoir to receive a lead, a reciprocable lead tube integrally formed with the hopper and aligned therewith, clutch mechanism for holding the lead, a lead tube to which the clutch mechanism is attached, a rack to operate the clutch, and means to move the rack to reciprocate the lead tube and feed the lead received.

75 6. In a pencil, the combination of an extending reciprocable member, a pinion carried by the re-

ciprocable member, a lead feeding member, and means cooperating with the pinion to translate the movement of the reciprocating member into a greater movement of the lead feeding member.

7. In a pencil, the combination of an extending reciprocable member, a pinion carried by the reciprocable member, a lead feeding member, and means cooperating with the pinion to translate the movement of the reciprocating member into a movement of reciprocation of the lead feeding member which is substantially double that of the reciprocable member.

8. In a pencil, the combination of an extending reciprocable member, a pinion movable therewith, a fixed rack engaging the pinion, a movable rack engaging the pinion, and means operated by the movement of the movable rack to feed a lead.

9. In a pencil, the combination of a hollow point supporting tube adapted to reciprocate a spring normally holding the point supporting tube in its extended position, a lead tube adapted to reciprocate in the point supporting tube, a pinion movable with the point supporting tube, a fixed rack engaging the pinion, a movable rack engaging the pinion, and means attached to the lead tube and the movable rack to clutch a lead in one direction of movement of the rack and release it in the other direction.

10. In a pencil, the combination of a reservoir for leads, a hopper located in the reservoir to receive a lead, a reciprocable lead tube integrally formed therewith, an extending reciprocable member, a pinion movable therewith, a fixed rack engaging the pinion, a movable rack engaging the pinion, and connected with the lead tube, and means operable by the movement of the movable rack to feed the lead.

11. In a pencil, the combination of a reservoir for leads, a hopper located in the reservoir to receive a lead, a reciprocable lead tube integrally formed therewith, a clutch for holding the lead, an extending reciprocable member, a pinion movable therewith, a fixed rack engaging the pinion, and a movable rack engaging the pinion and adapted to actuate the clutch.

12. In a pencil, the combination of a hollow point supporting tube adapted to reciprocate, a spring normally holding the point supporting tube in its extended position, a reservoir for leads, a hopper located in the reservoir to receive a lead by rotation of the pencil, a lead tube adapted to reciprocate in the point supporting tube and to which the hopper feeds, a pinion movable with the point supporting tube, a fixed rack engaging the pinion, a movable rack engaging the pinion, and means attached to the lead tube and the movable rack to clutch a lead in one direction of movement of the rack and release it in the other direction to feed a lead through the hollow point supporting tube upon reciprocation of the point supporting tube.

13. In a pencil, a reservoir for leads, a reciprocable lead tube in communication with the reservoir, means in said reservoir to feed leads to the lead tube, a clutch for holding the lead with respect to said tube, and means to reciprocate the lead tube to project the lead.

14. In a pencil, a reservoir for leads, a reciprocable lead tube in communication with the reservoir, means in said reservoir to feed leads to the lead tube, a clutch for holding the lead in the tube, and means to reciprocate the lead tube to project the lead.

75 15. In a pencil, a reservoir for leads, a reciproc-

cable lead tube in communication with the reservoir, means in said reservoir to continuously feed leads to the lead tube, a clutch for holding the lead in the tube and means to reciprocate the lead tube to project the lead.

16. In a pencil, a reservoir for leads, a reciprocable lead tube in communication with the reservoir, means to feed leads to the lead tube, a clutch for holding the lead with respect to said tube, a rack to operate the clutch, and means

to move the rack to reciprocate the lead tube to project the lead.

17. In a pencil, a reservoir for leads, a reciprocable lead tube in communication with the reservoir, means in said reservoir to feed leads to the lead tube, a clutch for holding the lead with respect to said tube, a rack to operate the clutch, and means to move the rack to reciprocate the lead tube to project the lead. 5

JESSE J. ROBBINS. 10
